UNITED STATES PATENT OFFICE.

STEFANO CHIARELLO, OF BROOKLYN, NEW YORK.

CAR STAKE.

Application filed July 27, 1927. Serial No. 208,831.

This invention relates to improvements in car stakes, and more particularly to telescopic car stakes for flat and gondola railway cars.

5 The primary object of the invention is to provide a telescopic car stake which is extremely simple and durable in construction as well as efficient in use.

Another object is to provide an improved 10 telescopic car stake embodying means for permitting the same to be readily set and maintained in extended condition.

A still further object is to provide an improved telescopic car stake having means 15 for permitting the same to be closed and placed in set position as to not be in the way when not in use and when the car is used for a purpose not requiring stakes.

Other objects will become apparent as 20 the nature of the invention is better understood, and the same consists in the novel form, combination and arrangement of parts hereinafter more fully described, shown in the accompanying drawings and claimed.

25 In the drawings, wherein like reference characters indicate corresponding parts throughout the several views,

Figure 1 is a fragmentary transverse sectional view of a flat bottom car equipped 30 with opposed stakes constructed in accordance with the present invention, the stakes being in rear elevation and shown in extended condition;

Figure 2 is a fragmentary side elevational 35 view showing a pair of the stakes of Figure 1 upon the same side of the car, the stakes being in collapsed condition;

Figure 3 is an enlarged view partly in front elevation and partly in section on 40 line 3—3 of Figure 2;

Figure 4 is an enlarged horizontal section on line 4—4 of Figure 3;

Figure 5 is a view similar to Figure 3 with the stake in extended condition;

45 Figure 6 is a vertical section on line 6—6 of Figure 5;

Figure 7 is a vertical section taken on line 7—7 of Figure 3;

Figure 8 is a fragmentary inside elevational view of the upper end portion of the stake when in collapsed condition and looking toward the left of Figure 4;

Figure 9 is a fragmentary transverse sectional view of a gondola car equipped with 55 a telescopic stake constructed in accordance

with the present invention, the stake being in collapsed condition;

Figure 10 is a central vertical section taken upon line 10—10 of Figure 9;

Figure 11 is a view similar to Figure 9 60 with the stake in extended condition; and

Figure 12 is a vertical section taken upon line 12—12 of Figure 11.

Referring more in detail to the drawings, the present car stake includes telescopically 65 associated lower and upper sections 5 and 6, and the lower section 5 embodies a pair of spaced parallel side plates rigidly connected adjacent their forward vertical edges by means of a vertical transverse wall 9 terminating short of the upper ends of the side members 7 and 8 as clearly shown in Figures 3, 6 and 7, and also rigidly connected at their rear vertical edges and at their 70 upper ends by means of a transverse web 10. 75

The space between the wall 9 and web 10 and between the side members 7 and 8 is such as to snugly slidably accommodate the upper section 6 when the latter is slid downwardly into the lower section 5 to the collapsed condition of Figures 3 and 7, and 80 said upper section 6 of the stake embodies

a bar of I-beam formation, the outer surfaces of the flanges of which are adapted to flatly engage the inner surfaces of the side 85 members 7 and 8 as shown more clearly in Figures 3 and 4. The flanges of the upper stake section 6 are provided with opposed vertical slots in the lower ends thereof as at

11, at the inner side of the web 12 of said 90 stake section 6, so that when the latter is elevated, then shifted laterally inwardly, and then lowered, the upper end of the wall 9 will seat in the slots 11 for holding the upper stake section 6 in elevated position as 95

shown in Figures 5 and 6. Connecting the upper ends of the side members 7 and 8 of the lower stake section 5 and at the forward edges of said members 7 and 8 is a keeper 100 bar 13 having an inwardly offset central portion adapted to be engaged by a downwardly facing hook 14 carried by the web 12 of section 6, for holding the stake section 6 against lateral movement when the upper end of wall 9 is engaged in the slot 11, thus 105

more securely holding the upper stake section in elevated position. It will thus be seen that when the upper stake section is lifted, the hook 14 will be disengaged from the keeper bar 13 when the slotted lower 110

end of the stake section 6 is disengaged from the upper end of wall 9, thus permitting the stake section 6 to be shifted laterally outwardly and then lowered into the 5 lower stake section 5 between the wall 9 and the web 10. Suitable means is provided for limiting the lowering movement of the upper stake section downwardly into the lower stake section 5, and such means may comprise a vertical web 15 connecting the lower 10 ends of the members 7 and 8 and adapted to be received within the slots 11 as shown in Figure 7. However, such limiting means may embody a horizontal bottom wall 16 as 15 shown in Figures 10 and 12, connecting the lower ends of the members 7 and 8 and upon which the lower end of the stake section 6 is adapted to rest when in lowered collapsed position.

20 Slidably engaged with the inner flanges of the upper stake section 6 is a C-shaped slide 17 to the inner side of which is attached one end of a load-binding chain 18 whose other end is adapted to be attached 25 to a similar slide carried by the upper stake section of a stake alined therewith and mounted on the opposite side of the car. In this way, the slide 17 may be freely vertically adjusted to the height of the load so 30 that the load binding chain may be properly positioned in respect to the latter. The upper stake section 6 is preferably of such a length as to have its upper end terminate flush with the upper end of the 35 lower stake section 5 when in collapsed condition, and in order to permit the slide 7 to remain in engagement with the flanges of the upper stake section 6 when the latter is in lowered or collapsed condition, the inner member 7 of the lower stake section 5 is 40 provided with a notch or cut out 19 in its upper end within which the slide 17 will seat, as best illustrated in Figures 4, 7 and 8.

45 Referring more particularly to the embodiment of the invention shown in Figures 1 to 8 inclusive, the stake may be secured to the side sill 20 of a car having a flat bottom 21, by means of a swivel member embodying a bolt 22 having a ring member 23 slidably embracing the lower stake section 5. Rigidly provided upon the lower 50 end portion of the lower stake section 5 is a flange or collar 24 adapted to prevent the stake from being pulled upwardly through the swiveled ring 23 spaced from the extreme lower end of the stake section 5 to permit said lower end of the latter to seat 55 within a socket ring 25 when the stake is vertically disposed and lowered to the ring 60 23. The socket ring 25 is suitably rigidly attached to the sill 20 beneath the ring 23 of the swivel member and lowering movement of the stake is properly limited by engagement of the collar 24 with the socket ring 65 25. In this way, the stake is effectively

70 maintained in vertical position when in use, and by manually lifting the stake so that the lower end of the lower stake section 5 is disengaged from the socket ring 25, the stake may be swung forwardly and downwardly alongside the sill 20 below the bottom 21 to a horizontal inoperative position as indicated by dotted lines in Figure 2. A suitable stop member 26 may be mounted 75 upon the sill 20 to limit the lowering movement of a collapsed stake to a horizontal position as shown, and when thus disposed, the stake will be entirely out of the way so as to not interfere with use of the car for other purposes than those requiring the use of stakes. It will be understood that the swivel ring 23 turns about the axis defined by bolt 22 when the stake is swung from operative to inoperative position or vice versa.

75 As shown in Figures 9 to 12 inclusive, the members 23, 24 and 25 may be omitted, and the lower section 5 of the stake may be rigidly secured to the inner side of the side wall 27 of a gondola car, upon the bottom 28 of the latter. In this instance, the side member 8 of the lower stake section may be bolted to the side wall 27 of the car as at 29, the bottom wall 16 of the lower stake section resting flatly upon the bottom 28 of the car. Further, in this instance, the lower stake section 5 is substantially equal in height to the height of the wall 27, thus resulting in the projection of the stake above the wall 27 only when the stake is in extended position. Otherwise, the form of the invention shown in Figures 9 to 12 inclusive correspond to the construction above described in connection with Figures 1 to 8 inclusive.

80 From the above description it is believed that the construction and advantages of the invention will be readily understood and appreciated by those skilled in the art, minor changes may be made without departing 100 from the spirit and scope of the invention as claimed.

85 What I claim as new is:—

1. In a telescopic car stake, a lower section embodying a pair of spaced side members rigidly connected adjacent their forward edges by means of a vertical transverse wall terminating at its upper end below the upper ends of said side members, a transverse web rigidly connecting the upper ends 110 of said side members at their rear edges, and a transverse keeper bar connecting the upper ends of said side members at their forward edges and having an inwardly offset intermediate portion, an upper section of I- 115 beam formation slidable into the lower section between said vertical wall and said transverse web and having slots in the lower ends of its flanges adapted to receive the upper end of said vertical wall when the 120

125 upper end of said vertical wall when the 130

- upper section is slightly lowered after being elevated and shifted laterally and inwardly, a downwardly facing hook on the web of said upper section adapted to engage the inwardly offset portion of said keeper bar when said upper section is so slightly lowered, and means to limit downward movement of the upper section into said lower section when the stake is collapsed. 5
2. In a telescopic car stake, a lower section embodying a pair of spaced side members rigidly connected adjacent their forward edges by means of a vertical transverse wall terminating at its upper end below the upper ends of said side members, a transverse web rigidly connecting the upper ends of said side members at their rear edges, and a transverse keeper bar connecting the upper ends of said side members at their forward edges and having an inwardly offset intermediate portion, an upper section of I-beam formation slidable into the lower section between said vertical wall and said transverse web and having slots in the lower ends of its flanges adapted to receive the upper end of said vertical wall when the upper section is slightly lowered after being elevated and shifted laterally and inwardly, a downwardly facing hook on the web of said upper section adapted to engage the inwardly offset portion of said keeper bar when said upper section is so slightly lowered, and means to limit downward movement of the upper section into said lower section when the stake is collapsed, said last named means embodying a transverse vertical web connecting the lower ends of said side members and adapted to seat in said slots. 10
3. In a telescopic car stake, a lower section embodying a pair of spaced side members rigidly connected adjacent their forward edges by means of a vertical transverse wall terminating at its upper end below the upper ends of said side members, a transverse web rigidly connecting the upper ends of said side members at their rear edges, and a transverse keeper bar connecting the upper ends of said side members at their forward edges and having an inwardly offset intermediate portion, an upper section of I-beam formation slidable into the lower section between said vertical wall and said transverse web and having slots in the lower ends of its flanges adapted to receive the upper end of said vertical wall when the upper section is slightly lowered after being elevated and shifted laterally and inwardly, a downwardly facing hook on the web of said upper section adapted to engage the inwardly offset portion of said keeper bar when said upper section is so slightly lowered, means to limit downward movement of the upper section into said lower section when the stake is collapsed, a ring swiveled to the side of the car and slidably embracing the lower section, a fixed collar on the lower section below the swiveled ring, and a socket ring fixed to the car below the swiveled ring adapted to receive the lower end of the lower section to hold the stake in a vertical position with the fixed collar resting on the socket ring and spaced from the swiveled ring sufficiently to permit elevation of the stake to disengage the lower end of the lower section from said socket ring. 15
4. In a telescopic car stake, a lower section embodying a pair of spaced side members rigidly connected adjacent their forward edges by means of a vertical transverse wall terminating at its upper end below the upper ends of said side members, a transverse web rigidly connecting the upper ends of said side members at their rear edges, and a transverse keeper bar connecting the upper ends of said side members at their forward edges and having an inwardly offset intermediate portion, an upper section of I-beam formation slidable into the lower section between said vertical wall and said transverse web and having slots in the lower ends of its flanges adapted to receive the upper end of said vertical wall when the upper section is slightly lowered after being elevated and shifted laterally and inwardly, a downwardly facing hook on the web of said upper section adapted to engage the inwardly offset portion of said keeper bar when said upper section is so slightly lowered, means to limit downward movement of the upper section into said lower section when the stake is collapsed, a ring swiveled to the side of the car and slidably embracing the lower section, a fixed collar on the lower section below the swiveled ring, and a socket ring fixed to the car below the swiveled ring adapted to receive the lower end of the lower section to hold the stake in a vertical position with the fixed collar resting on the socket ring and spaced from the swiveled ring sufficiently to permit elevation of the stake to disengage the lower end of the lower section from said socket ring. 20
- In testimony whereof I affix my signature.
